UNITED STATES PATENT OFFICE.

JOHN ALLISON, OF ST. MARTINSVILLE, LOUISIANA.

IMPROVEMENT IN CANE-COVERERS.

Specification forming part of Letters Patent No. 27,339, dated March 6, 1860.

To all whom it may concern:

Be it known that I, JOHN ALLISON, of St. Martinsville, in the parish of St. Martin and State of Louisiana, have invented a new and Improved Machine for Covering Cane; and I do hereby declare that the following is a full, clear, and exact description of the same, reference being had to the annexed drawings, making a part of this specification, in which—

Figure 1 is a longitudinal vertical and central section of my invention; Fig. 2, a plan or top view of the same.

Similar letters of reference indicate corresponding parts in the two figures.

The object of this invention is to obtain a machine for covering cane that will during the operation pulverize the earth and cause the seed to be covered with a loose, light, and pliable mold, permeable to air and moisture, thereby greatly favoring its germination.

The invention relates to an improvement on a machine for covering cane for which Letters Patent bearing date November 24, 1857, were granted to me; and it consists in a peculiar arrangement and combination of blades or shares, rotary harrows, a stationary harrow, and a roller provided with a scraper and fitted with one or more rotary harrows in a swinging frame, whereby the desired end is attained.

To enable those skilled in the art to fully understand and construct my invention, I will proceed to describe it.

A A are two pieces of boards or planks, which are secured at a proper distance apart by traverse-bars, *a a'*, said boards or planks having an oblique position relatively with each other, so that the space B between their back ends will be narrower than the space C between their front ends, as shown clearly in Fig. 2. To the lower edge of each board or plank A an iron or steel blade, D, is attached. These blades have a slight inclination downward and inward toward each other, as will be understood by referring to Fig. 2.

E is a frame, which is attached to the back parts of the boards or planks A A by bolts *a' a'*, the frame being allowed to swing freely on said bolts. In the back part of the frame E a concave roller, F, is placed, and a scraper, G, is secured in the back part of the frame, said scraper being behind the roller F, as shown

more particularly in Fig. 1. In the frame E, and directly in front of the roller F, two rotary harrows, H I, are placed, one in front of the other, the front harrow, H, being rather more elevated than the back one, I, for the reason hereinafter stated.

Between the two boards or planks A A a rotary harrow, J, is placed, said harrow being parallel with the traverse-bars *a a'*, as shown clearly in Fig. 2, and somewhat above the blades or shares D, as shown clearly in Fig. 1.

To the front parts of the boards or planks A A a V-shaped harrow, K, is attached. This harrow is formed by having suitable teeth, c, in a bar, c', the inner parts of which are attached by pivots *d* one to each board or plank A, and the ends terminating in slotted arms *e*, through which set-screws *f* pass into the boards or planks. The harrow K may be adjusted higher or lower by regulating the screws *f*. The slotted arms *e* are clearly shown by the dotted lines in Fig. 1.

To the front traverse-bar *a* of the boards or planks A A a draft-chain, L, is attached, and handles M M are secured to the bars *a a'*.

The boards or planks A A, blades or shares D D, frame E, roller F, and scraper G were used in the patented machine previously referred to; but the rotary harrows H I J, arranged as shown, and the stationary adjustable harrow K are new.

The operation is as follows: The team is hitched to the machine, which is placed directly over the row of cane or seed to be covered. As the implement moves along the dirt is scraped up by the blades D, accumulated, and raised by the boards A and through the opening B. The rotary harrow J, which is operated only by the resistance offered to it by the earth during the movement of the implement, pulverizes the earth, so that it will fall into the furrow in which the seed is planted and cover the same. The rotary harrows H I still further pulverize the earth after the seed is covered, the harrow H breaking the larger lumps or clods of earth and the lowermost harrow, I, breaking the small lumps. The roller F compresses the earth on the seed and leaves a convex ridge. The scraper G, preventing earth adhering to the roller F, and the front stationary adjustable harrow, K, break all clods

of earth and prepare it properly to receive the action of the blades or shares D D and harrow J.

The swinging frame E admits of the roller P and harrows H I conforming to the inequalities of the surface of the ground.

I do not claim the boards or planks A A with blades D D attached, nor the roller-frame E with the roller F and scraper G, for they have been previously used; but

I do claim as new and desire to secure by Letters Patent—

The boards or planks A A, with blades D D, rotary harrow J, and adjustable harrow K attached, the frame E, provided with the roller F, scraper G, and one or more rotary harrows, H I, the whole being combined and arranged for joint operation, as and for the purpose set forth.

JOHN ALLISON.
